W. A. Wood,
Mower.

No. 33,862

Patented Dec. 3, 1861

W. A. Wood,
By A. B. Livingston.

UNITED STATES PATENT OFFICE.

W. A. WOOD, OF HOOSICK FALLS, NEW YORK.

IMPROVEMENT IN HARVESTERS.

Specification forming part of Letters Patent No. 33,862, dated December 3, 1861.

To all whom it may concern:

Be it known that I, W. A. WOOD, of Hoosick Falls, in the county of Rensselaer and State of New York, have invented a new and useful Improvement in Harvesting-Machines; and I do hereby declare the following to be a full, clear, and exact description of the same, reference being had to the accompanying drawings, making a part of this specification, in which—

Figure 1 represents in perspective so much of a harvesting-machine as will illustrate my invention. Fig. 2 represents a top plan of the same. Fig. 3 represents in perspective a modification of the plan of raising and lowering the finger-bar. Fig. 4 represents a section through the ground-wheel of Figs. 1 and 2, showing how the lifting connection between the lever and the finger-bar or its plate is arranged.

Similar letters of reference, where they occur in the separate figures, denote like parts of the machine in all cases.

The object in the construction of harvesting-machines is to keep the cutting apparatus as nearly in line with the axle or center of the drive-wheel as possible, and at the same time to so unite the finger and cutter bar to the main frame as that they may be raised up or let down as circumstances may require; and my invention consists in uniting the finger-bar to a bent bar at or near the line of the center or axle of the drive-wheel, said bent bar being in turned hinged by rods to the stubble side of the main frame, so that it, as well as the finger-bar, may rise and fall, or be raised up and held thus raised up or let down at pleasure by the driver or conductor from his seat.

To enable others skilled in the art to make and use my invention, I will proceed to describe the same with reference to the drawings.

A represents a main frame, supported on a drive-wheel, B, and a ground or supporting wheel, C, the journal of the latter wheel being set slightly in rear of that of the drive-wheel, and the diameter also of the ground-wheel being less than that of the drive-wheel, for the purpose of allowing the cutting apparatus to be placed in line with or nearly in line with the axle D of the drive-wheel B, as seen more distinctly in the plan, Fig. 2. To the front

and rear cross-pieces of the main frame, and at or near the stubble side thereof, as at a a, are hinged the two rods b b', their other ends being fastened, respectively, to the front and rear ends of a bent bar, E, that serves as a shoe or runner and as a support for a short finger-bar, F, which is attached to it in or near its center portion. One of the rods, b, is made to move through a guide, as at c, for the purpose of preventing the finger-bar and cutting apparatus from twisting or straining; but instead of a loop-guide such as shown at c, the axle d of the ground-wheel may be extended beyond the outer face of the wheel and a brace-rod be extended from such projection to a point, e, on the bent bar, and be secured there, which serves to brace the finger-bar, while it avoids the friction due to the rod b moving through the loop-guide.

In Fig. 1 the ground or supporting wheel C is hung on an axle, d, while in Fig. 3 it is represented as a caster-wheel. Either will answer the purpose, but require modified arrangements of the lifting devices. In Figs. 1 and 2 the axle d of the ground-wheel C is hollow, as seen in Fig. 4, and through this hollow axle passes a shaft, f, which has the lever G fastened to its inner end, while its outer end carries a bent arm, g, to which, by means of a link, h, the bent bar E is attached, and thus by means of the lever G the driver or conductor from his seat H can raise or lower the finger-bar and its several connected parts. A second lever or brace, I, may be used in connection with that G, with suitable catches, i, thereon to hold up the finger-bar after it is raised to the desired height.

In Fig. 3 the lever G is attached to a rod or shaft, f, supported at k. This rod carrying the arm g and link h, by which the finger-bar is raised, in both cases the lifting is done at or near the line of the axle of the driving-wheel. In Fig. 3 the lever and its arm are so arranged as that the weight of the finger-bar, when raised up, is upon the same side of the fulcrum as the lever is, and hence tends to hold the lever down and itself up, without other fastening.

J is the tongue by which the machine is drawn.

I have not shown the gearing nor the cutting apparatus which it is intended to drive.

These may be any of the kinds now known or in use, and arranged on the main frame in any well-known manner of using drive-gear.

Having thus fully described my invention, what I claim therein as new is—

Connecting a short finger-bar to the bent bar E at or near the line of the axle or center of the main driving-wheel, in combination

with the hinging of said bent bar to or near to the stubble side of the main frame by rods or braces, substantially in the manner and for the purpose herein described.

W. A. WOOD.
